CLOSURE CAP AND PACKAGE

Robert C. Hanson, Connellsville, Pa., assignor to
Anchor Hocking Glass Corporation, Lancaster,
Ohio, a corporation of Delaware

Application March 22, 1948, Serial No. 16,227

6 Claims. (Cl. 215—40)

1

The present invention relates generally to closure caps for receptacles and particularly to closure caps of the "force-fit" type adapted to be pressed downwardly over the upper end of a receptacle or container to form a side seal around the exterior upper portion of the receptacle.

Where closure caps of the reformable skirt type are applied over container mouths and the cap skirts thereafter reformed to produce a seal against a container sealing zone it is generally feasible to form a seal sufficiently tight as to prevent leakage of pressure from the atmosphere into the container to thereby destroy a container vacuum. In the reformation of such cap skirts the skirt moves inwardly until a gasket is tightly squeezed between the container neck and the closure cap skirt. While closure caps of the reformable skirt type are thus desirable they are nevertheless objectionable in that, among other reasons, it is difficult to form sealed packages with the same rapidity as with closures which are pushed down or force-fitted; relatively complicated machinery is required to reform the cap skirts to make tight seals, and relatively complicated machinery is required for producing a vacuum condition prior to and during application and reforming of the closure cap skirt.

For the foregoing reasons closure caps of the pushed down, side seal type are extensively utilized for covering the upper ends of vacuumized receptacles filled with various food products. Such closure caps are more readily applied and the containers to which they are applied may be more readily vacuumized.

With closure caps of the force-fit side seal type manufacturing tolerance difficulties have been experienced which interfere with application of caps so as to maintain a desired vacuum seal. It is frequently difficult to form or maintain a suitable vacuum seal with side seal containers by reason of the fact that individual receptacles or containers of a standard or given size have slightly different sealing zone dimensions, as well as at other portions thereof. As a practical manufacturing matter various tolerances must be allowed and while a given lot of containers may be of a same true "standard" size, they may individually still be of slightly varying dimensions. Manufacturing tolerances generally have been kept at a minimum consistent with practical conditions of production, but this as well as slight out-of-roundness and other manufacturing defects still tend to impair the formation and maintenance of vacuum seals. Even though a closure cap may be fitted over a container mouth such variations in effective sizes of container

2

sealing zones render it difficult to maintain hermetic or vacuum seals; air tends to leak past a sealing gasket into the container to cause spoilage of the contents.

Even in those instances where the container is of approximately an exact standard size, difficulty in sealing and maintaining a vacuum in the container arises due to tolerance variations extant in the closure caps and sealing gaskets themselves. While these dimensional variations may seem slight they are in many cases of sufficient magnitude to impair maintenance of a vacuum within a capped container.

In actual practice combinations of all three 15 of the above dimensional variations occur. The containers, gaskets and closure caps embody dimensional tolerance variations from a given standard, rather than merely a container alone or a closure cap alone or a gasket alone. Where 20 a minimum size container is used with a gasket having a maximum effective inside diameter, forming and maintaining a vacuum seal is difficult; air tends to leak into the container through the relatively loose seal. Where the container 25 has a sealing zone diameter of maximum size and is used with a gasket and closure cap of minimum effective diameter, it is often difficult to force the cap and gasket downwardly over the container mouth.

The present invention aims to overcome or 30 minimize the above and other difficulties or disadvantages and to securely maintain vacuum or hermetic seals by providing a closure cap adapted to so retain a sealing gasket as to effectively seal 35 a container with maximum allowable tolerances or dimensional variations, and regardless of existing tolerance dimensions of the container per se, of the closure cap per se, of the gasket per se or of all three in combination. The present closure cap aims to provide for maintaining a gasket 40 so that the gasket may seal containers of minimum dimensional characteristics and to provide for "absorbing" what may be termed surplus gasket material when applied to and sealing containers of maximum dimensional variations.

An object of the present invention is to provide 45 a new and improved closure cap.

Another object of the invention is to provide an 50 improved closure cap adapted to form a seal around a side sealing zone adjacent the upper end of a container.

Another object of the invention is to provide an 55 improved closure cap adapted to effectively seal containers with dimensional tolerances or manufacturing variations.

Another object of the invention is to provide an

improved closure cap adapted to absorb excess gasket material when the closure is applied to oversize containers.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a fragmentary view, partly in section, illustrating the present closure cap applied to a container;

Fig. 2 is an enlarged fragmentary sectional view illustrating the closure cap of Fig. 1;

Fig. 3 is a sectional view taken along the line 3—3 of Fig. 2 showing the cap before application to a container;

Fig. 4 is an enlarged fragmentary horizontal sectional view illustrating the present closure cap sealed on a container;

Fig. 5 is an enlarged fragmentary horizontal sectional view illustrating the present closure cap sealed on a container;

Fig. 6 is an enlarged fragmentary horizontal sectional view illustrating a slightly different form of the invention;

Fig. 7 is an elevational view illustrating a modified form of closure cap embodying the invention;

Fig. 8 is an enlarged fragmentary sectional view taken along the line 8—8 of Fig. 7;

Fig. 9 is an elevational view of another modified form of closure cap embodying the invention; and

Fig. 10 is an enlarged fragmentary sectional view taken along the line 10—10 of Fig. 9.

Referring more particularly to Fig. 1, there is shown a sealed package comprising a container or receptacle 1 having an upwardly facing mouth over which is positioned a closure cap 2. An airtight seal is formed by a rubber or other gasket 3 located between the lower portion of the cap skirt 4 and a container side wall sealing zone 5. The container or receptacle 1 is generally made of glass and may have an upper tapered portion 7 to facilitate application of the closure cap 2 with the gasket 3 carried thereby, the gasket seating against the exterior surface of the sealing zone 5. The container of Fig. 1 is illustrative of one shape which may be sealed by closure caps of the present invention; any other suitable type of neck or sealing zone may be used. The closure cap is shown made from relatively thin sheet metal as such is relatively inexpensive and may be readily formed into the desired shape. An outwardly projecting ledge 8 spaced below the skirt of the cap 2 provides a pry-off ledge against which a knife blade or the like may be fulcrumed to pry the cap upwardly for removal of it from the container.

A recessed portion 10 at the top of the cap connects by an inclined portion 11 with an upstanding ridge or rim 13 to form a dished or inset stacking seat. The dished or inclined portions 10 and 11 are adapted to receive the bottom of a container to facilitate vertical stacking of containers on a shelf. The closure cap is preferably sealed to the container while the mouth of the latter is filled with steam, the steam subsequently condensing and creating a partial vacu-

um which tends to pull the closure cap downwardly onto the container. In sealed position on a container the sealing zone of the container presses outwardly against the inner circumference of the gasket 3 and the closure cap.

Where the skirt portion 4 of the closure cap and the cooperating container sealing zone 5 are of exactly standard dimensions there results a correct or optimum squeezing of the gasket and sealing of the closure cap to the container in such manner as to prevent leakage of air under pressure from the atmosphere past the sealing zone and into the vacuumized container. If the container be slightly undersize, or the closure cap slightly oversize, intermediate gasket 3 is not gripped with optimum tightness and there is a tendency or possibility of air leaking into the container past the sealing zone. In other instances the reverse condition may exist namely a minimum size of cap and maximum size of container; in this case difficulty is experienced in forcing the relatively small interior diameter gasket downwardly over the sealing zone 5. Various "in between" conditions exist intermediate the two aforementioned extreme conditions. The desirability or need of having closely correct dimensions may be appreciated when it is realized that a vacuum of more than twenty inches of mercury is quite generally utilized and that vacuum in excess of twenty-five inches of mercury are common.

The sealing gasket 3 carried by the cap is of preferably rectangular or square cross section and abuts at its upper horizontal portion against the underside of a horizontally extending ledge portion 14; its bottom surface is held or supported by an inwardly extending edge 16. The portions 14 and 16 are preferably uninterrupted and hold the gasket 3 against change in vertical dimensions. When the closure cap is pushed down over a container mouth the gasket 3 is placed under compression between the container side wall and the skirt portion 4 of the closure cap, as well as between the substantially horizontal edges 14 and 16. The amount of horizontal compression of the gasket 3 depends upon the particular existing differences in diameters between that of the sealing zone 5 and that at the cap skirt portion 4. Where the effective distance between the sealing zone 5 and the inside of the cap skirt 4 is small, the gasket 3 is placed under a relatively high compression; where the distance between the exterior surface of the sealing zone 5 and the interior surface of the cap skirt 4 is comparatively great, the gasket 3 is placed under lesser compression. With previous closure caps the gasket sealing pressure or "gasket-squeezing-together" pressure varies from a minimum to a maximum, with no provision for accommodating gasket material where the pressure tends to become excessive and to yet create a tight seal at an opposite extreme condition.

In order to overcome or minimize such difficulties, the offset vertical skirt portion 4 of the present cap is provided with circumferentially spaced gasket supporting or inwardly extending portions 17 (Fig. 3) separated from each other by circumferentially disposed spaces or outwardly extending portions 19. While the portions 17 are referred to as being inwardly extending it will be understood that this is for purposes of convenience in description, as the portions 17 may be provided by moving the portions 19 relatively outwardly, to leave the portions 17 project-

ing inwardly. The effect is to provide around the circumference of the offset skirt zone 4 a plurality of inwardly disposed, circumferentially spaced, vertically extending portions 17 separated by spaces or recesses 20. The interior dimension of a particular standard size closure cap, measured across inwardly extending portions 17, is such as to accommodate and seal the gasket 3 against a container of maximum tolerance with which the cap will be used, even in those instances where the closure cap per se or gasket per se may embody a minimum tolerance dimension.

Where the present new closure cap 2 is on its container, regardless of the actually embodied tolerance dimensions of the cap and gasket and container, the gasket 3 carried by the cap is pressed outwardly by the container sealing zone so that some of the rubber gasket material moves into the spaces or recesses 20 (Fig. 4). Where a minimum tolerance size container and a maximum tolerance size closure cap and gasket are used in combination, the gasket is pressed into the recesses 20 to some such position as is indicated in Fig. 4. As the dimensional characteristics of the closure or gasket or container, or all three together, vary so as to decrease the distance intermediate the inside of the gasket backing portions 17 and the sealing zone of the container, a greater quantity of gasket material is urged or pressed into the circumferentially spaced recesses 20; Fig. 7 illustrates a condition wherein sufficient "surplus" gasket material has been forced into recesses 20 to completely fill them.

The amount of "surplus gasket material" varies with the existing dimensional tolerance characteristics of the individual container, individual gasket, and individual closure cap.

A very desirable feature which results from the evenly spaced arrangement of the alternately disposed backing portions 17 and recesses 20 is the substantially uniformly distributed sealing pressure against a container sealing zone throughout the height of the gasket backing portions 17. Gasket sealing pressure extends over a relatively wide band. With a 47 millimeter cap, a height for the vertical inwardly gasket backing portions 17 and recesses 20 of about one-tenth of an inch gives good results.

The inwardly extending upper and lower portions 14 and 16 tend to hold the shape and size of the offset skirt portion 4 and of the substantially vertical inset and outset portions 17 and 19. The portions 14 and 16 are preferably uninterrupted by gasket backing portions 17 or recesses 20 and act as strengthening or retaining bands which retain the offset skirt portion 4 against undue deformation consequent upon the exertion of sealing forces.

While the inwardly and outwardly extending portions 17 and 19 may be formed in the skirt at any convenient stage during manufacture it has been found convenient to form them, in any convenient manner, prior to turning inwardly the lower gasket supporting portion or ledge 16.

In Fig. 6 there is illustrated a horizontal cross section through the skirt of a closure cap and gasket 24 which is generally similar to that illustrated in Figs. 1 through 5. In Fig. 6, however, opposite sides 25 and 26 of the vertically extending gasket backing portions 23 and of the intermediate gasket receiving recesses 28 are of slightly differing shapes. Closure caps embodying such gasket backing portions, in an offset skirt similar to that illustrated in Figs. 1 and 2, have been

75 in a limiting sense.

found to perform very well in actual practice when sealed to containers. It may be that the different angular positions of the wall portions 25 and 26 tends to create a wedging or squeezing action which is directed longitudinally around the gasket 24. In operation the recesses or spaces 28 are adapted to receive or absorb greater or lesser quantities of surplus gasket material pressed therein by an inwardly positioned container sealing zone; the action is similar to that described in connection with the closure cap illustrated in Figs. 1 through 5.

A modified form of the invention is illustrated in Figs. 7 and 8 of the drawings. In this form the gasket backing feature is provided by circumferentially spaced inwardly extending projections 30, each of which is shown as having rounded surfaces of approximately hemispherical form. In many instances the projections 30 are not exactly hemispherical but, for purposes of convenience, the projections 30 will be described and otherwise referred to as of substantially hemispherical form. The staggered relationship of the inwardly extending projections 30 provides a backing effect which is distributed or extends over a relatively wide zone whereby, when the cap is pressed down over a container mouth, resultant sealing forces are distributed over substantially the full width of the sealing zone or corresponding height of the offset closure cap portion 31.

The form of the invention illustrated in Figs. 9 and 10 differs from that disclosed and described in connection with Figs. 7 and 8 in that the plurality of circumferentially spaced depressions or indentations 32 which form the gasket backing portions are of slightly larger diameter than the gasket backing portions 30 of Figs. 7 and 8, and also in that they are not arranged in the staggered relationship. The forms or arrangements illustrated in Figs. 1 through 8 are preferred to that illustrated in Figs. 9 and 10 since the gasket backing portions illustrated in the former group of figures applies sealing pressure more uniformly throughout the sealing zone of a container, however, in some instances, it may be desired to utilize the form illustrated in Figs. 9 and 10.

It will be seen that the present invention provides a new and improved force-fitted type of closure cap which is adapted to be sealed with receptacles or containers to provide an effective hermetic or vacuum seal in a greater number of instances than is true of previous closure caps and containers. An offset gasket-holding skirt has a plurality of circumferentially spaced gasket backing or supporting portions with intermediate gasket receiving recesses. The recesses absorb surplus gasket material when the gasket is placed under compression by being applied to a container. The amount of surplus gasket material squeezed into the circumferentially spaced surplus-receiving portions varies, depending upon the dimensional tolerance characteristics of the particular closure cap, gasket, and container to which the cap and gasket are applied. Sealing pressure is distributed substantially uniformly throughout the height and length of the sealing zone.

As various changes may be made in the form, construction and arrangement of the parts herein without departing from the spirit and scope of the invention and without sacrificing any of its advantages, it is to be understood that all matter herein is to be interpreted as illustrative and not

Having thus described my invention, I claim:

1. A container closure of the type adapted to be applied to a container to form a seal against a side wall thereof without reformation of the closure skirt, comprising a cover portion, a depending skirt having a substantially smooth and uninterrupted upper portion and a lower portion of greater diameter than said upper portion, said lower portion having around its periphery intermediate top and bottom edges thereof a plurality of circumferentially spaced inset gasket backing portions separated from each other by unoccupied gasket-receiving spaces, a substantially smooth and uninterrupted ledge connecting the top edge of said lower portion with a bottom part of said upper portion, a substantially smooth and uninterrupted ledge extending inwardly from the bottom edge of said lower portion, and an annular elastic gasket lying wholly intermediate said ledge portions and supported at circumferentially spaced locations around its outer periphery on said inset backing portions, portions of the gasket circumferentially intermediate said spaced locations bridging said gasket-receiving spaces of the depending skirt.

2. A container closure of the type adapted to be applied to a container to form a seal against a side wall thereof without reformation of the closure skirt, comprising a cover portion, a depending skirt provided with a lower portion having around its periphery and extending across the major portion of its width a plurality of circumferentially spaced inset gasket backing portions separated from each other by unoccupied gasket-receiving spaces, an upper skirt portion of lesser diameter than said lower portion and uninterrupted by gasket backing portions, a substantially uninterrupted ledge connecting the top edge of said lower portion with a bottom part of said uninterrupted upper portion, a substantially uninterrupted ledge extending inwardly from the bottom edge of said lower portion, and an annular elastic gasket lying wholly intermediate said ledge portions and resting at circumferentially spaced locations around its outer periphery against said inset backing portions, portions of the gasket circumferentially intermediate said spaced locations bridging said gasket-receiving spaces of the depending skirt.

3. A container closure as set forth in claim 2, in which said inset gasket backing portions have generally convex inwardly disposed surfaces and extend generally vertically across said lower portion of the skirt.

4. A container closure as claimed in claim 1,

55

in which said inset gasket backing portions have substantially hemispherical inwardly disposed surfaces.

5. A container closure as claimed in 1, in which said inset gasket backing portions have substantially hemispherical inwardly disposed surfaces and are located in substantially staggered relationship.

10 6. A sealed package comprising a container having an annular sealing zone extending about its side wall below the upper edge thereof, a closure cap having a cover portion over the container mouth, a skirt depending from the cover portion having a substantially uninterrupted upper portion and a lower portion of greater diameter than said upper portion spaced outwardly from the container sealing zone, said lower portion having around its periphery intermediate top and bottom parts thereof and generally coextensive with said sealing zone a plurality of circumferentially spaced substantially vertically disposed inset gasket backing portions separated from each other by gasket-receiving spaces, a substantially uninterrupted ledge connecting the top 15 part of said lower portion with a bottom part of said uninterrupted upper portion, a substantially uninterrupted ledge extending inwardly from the bottom part of said lower portion, and an annular elastic gasket lying wholly intermediate and confined between said ledge portions and resting at circumferentially spaced locations around its outer periphery against said circumferentially spaced inset backing portions, portions of the gasket circumferentially intermediate said spaced 20 locations being squeezed at least partially into said gasket-receiving spaces by the container sealing zone.
